UNITED STATES PATENT OFFICE.

FRIEDRICH PELZER, OF DORTMUND, PRUSSIA, GERMANY.

CENTRIFUGAL FAN.

SPECIFICATION forming part of Letters Patent No. 416,070, dated November 26, 1889.

Application filed December 11, 1888. Serial No. 293,279. (Model.) Patented in Germany August 5, 1887, No. 43,318, and in England October 10, 1887, No. 13,678.

To all whom it may concern:

Be it known that I, FRIEDRICH PELZER, a subject of the Emperor of Germany, residing at Dortmund; Germany, have invented a new and useful Improvement in Centrifugal Fans, (for which Letters Patent have been obtained by me in Germany, No. 43,318, August 5, 1887, and in England, No. 13,678, provisional, of date October 10, 1887,) which improvement is fully set forth in the following specification and accompanying drawings.

My invention relates to improvements in centrifugal fans or ventilators, the object being the production of a device of the character mentioned which will be thoroughly effective for the purpose intended.

To attain the desired end the invention consists of a centrifugal fan or ventilator comprising a wheel having a closed end, with the spokes or arms thereof forming discharge-passages, and wings forming a screw for conducting the air to said passages, as herein-after described and specifically claimed.

Figure 1 represents a perspective view of a centrifugal fan or ventilator embodying my invention. Fig. 2 represents a front elevation thereof. Fig. 3 represents a diametrical section thereof. Fig. 4 represents a plan view of one of the wings. Fig. 5 represents sections thereof on lines respectively *a b c d e*.

Similar letters of reference indicate corresponding parts in the several figures.

Referring to the drawings, A designates a shaft on which the fan is mounted.

B designates the hub of the device, and C designates a cone secured to the hub and forming the closed end of the device.

D designates arms, spokes, or paddles secured to the hub and to the cone, the hub, cone, and spokes forming a wheel and the divisions formed by the spokes or arms forming discharge-passages D' for the air or fluid.

E designates a rim or band surrounding the upper edges of the spokes or arms and being secured thereto.

F designates the wings of the device, which are each formed of a triangular piece, one of the sides thereof being straight lined and the other two being convex, as shown in Fig. 4, and which are attached at their inner or straight-line ends to the spokes and at their outer ends secured to said rim.

From this construction it will be seen that a peculiar curve is given to the wings, forming pockets, which enables them to effectually draw in the air, and also that said wings discharge the air into the passages D'. It is also evident that by the peculiar shape of the wings and the manner of attaching them said wings will draw the air in at the center of the device and discharge it through the passages at the periphery thereof, this construction insuring a rapid and perfect exhaustion of the air or fluid.

Having thus described my invention, what I claim as new, and desire to secure by Letters Patent, is—

1. A centrifugal fan or ventilator having a conical closed end secured to a central hub, arms or spokes secured to said conical end and to said hub, a rim on one end of said arms, and wings secured to one end of said arms and to the inner face of the rim and to said hub, said parts being combined substantially as described.

2. The combination of a hub, a closed conical end piece secured thereto, arms radial of the hub secured thereto and to the end piece, a rim secured to the arms at one end, and wings consisting of triangular pieces secured to the end of the arms and to the inner side of the rim, forming pockets, substantially as described.

In witness whereof I have hereunto set my hand in presence of two witnesses.

FRIEDRICH PELZER.
